COMBINED LIVESTOCK OILER AND RUBBING POST

Henry S. Teitelbaum, Denver, Colo., assignor to Daytree
Manufacturing Company, Denver, Colo., a corporation
of Colorado

Filed Dec. 12, 1962, Ser. No. 72,823

Term of patent 14 years

(Cl. D12—2)

FIGURE 1 is a front elevation of the combined live-
stock oiler and rubbing post showing my new design;

FIGURE 2 is a side elevation taken from the right in
FIGURE 1;

FIGURE 3 is a side view of the upper portion looking
in the direction of arrow 3 in FIGURE 1; and,

FIGURE 4 is a bottom plan view thereof.

The rear of the combined livestock oiler and rubbing
post is substantially the same in appearance as the front.

I claim:

The ornamental design for a combined livestock oiler
and rubbing post, as shown and described.
